ATTORNEY

UNITED STATES PATENT OFFICE

WILLIAM B. SMITH WHALEY, OF NEW YORK, N. Y.; ISABELLE ELLIOTT WHALEY, EXECUTRIX OF SAID WILLIAM B. SMITH WHALEY, DECEASED, ASSIGNOR TO THE WHALEY ENGINE PATENTS, INC., OF NEW YORK, N. Y., A CORPORATION OF DELAWARE

STARTING VALVE

Application filed December 18, 1924, Serial No. 756,858. Renewed October 15, 1929.

My invention relates to valves designed to operate with air under high pressure, and of the poppet type, and more particularly to the valves controlling the supply of air under high pressure in starting large size internal combustion engines. My valve can also be used wherever the flow of liquids is to be controlled, especially if under high pressure.

10. Fig. 1 is a front view of the valve, partly in section.

Fig. 2 is a side view of the valve, also partly in section.

Referring to the drawing, it is seen that 15 my valve is entirely enclosed in a body, 1, and cap 2. The cap 2, is bolted to the upper portion of the body, 1, by means of a peripherally arranged series of bolts, 3, passing through a flange on the lower part 20 of the cap, 2, and a similar flange at the top of the body, 1. The cap, 2, may make a straight inlet connection to the body, 1, or an elbow, as shown, the particular form of the cap, 2, being no part of my invention, 25 as any form may be used. The body, 1, has a hollow interior, 4, in which is mounted a sleeve, 5. The sleeve, 5, is free to move longitudinally in the interior, 4, of the body, 1, and has concentrically secured therein 30 a spindle, 7, having a conical valve head, 8, at its upper end. The spindle, 7, passes through a spindle, 9, so that the head, 8, engages with the upper end of the spindle, 9, which forms a seat therefor, and which 35 spindle, 9, is also provided at its upper end with a conical head, 10, which finds a seat in the body, 1, or a collar, 30, inserted in the body for the purpose.

Passing radially through the head, 10, 40 I have one or more small ducts, 11, forming communications between that portion of the interior, 4, of the valve which lies above the outlet, 28, and the space immediately below the head, 8, of pin, 7. The spindle, 45 9, is screwed or otherwise secured concentrically into a cup 12, at its lower end. Above the cup, 12, and between it and a bearing, 6, for the spindle, 9, I provide a spring, 13, and below the cup, 12, and above the sleeve, 5, I provide a lighter spring, 14.

These two springs 13 and 14 place the valve heads 8 and 10 under an initial downward pressure,—the valve head, 10, having a greater downward pressure than the valve head, 8.

Pivoted to the lower side of the sleeve, 5, I provide a shoe, 15, which is secured in position by a transverse pin, 16, passing through the shoe, 15, and a lug, 17, on each side thereof, which latter I prefer to make integral with the sleeve, 5, as shown in Fig. 1. The shoe, 15, is free to rock on the pin, 16, through a given angle. The purpose of pivoting the shoe, 15, is obviously to enable it to ride properly on the cam, 18, irrespective of the annular position of the cam. Below the shoe, 15, I provide a cam, 18, which bears against it, and which is secured to or integral with a shaft, 19. In the drawing I show the cam, 18, in circular form, and mounted or secured eccentrically on the shaft, 19, as shown. To the left hand end of the shaft, 19, as shown in Fig. 1, I provide a crank, 20, keyed to the shaft, 19, whereby it is rotated. The opposite end of the shaft, 19, has a concentric, longitudinal recess, 21, in which I mount a spring, 22, bearing at one end against the bottom of the recess, 21, and at its opposite end against a plug, 23. The plug, 23, occupies a recess in the side of the bottom of the body, 1, as shown in Fig. 1, and is secured in position by a shouldered screw cap, 24, which bears against it at its center, by means of a projection, 25, provided for the purpose, on the screw cap. This puts the spring under tension and forces the shaft, 19, to the left as shown in Fig. 1.

The shaft, 19, is provided with a conical shoulder, 26, which bears against the chamfered inside edge of the bearing hole, 27, in the body, 1, through which the crank end of the shaft passes, by pressure exerted by the spring, 22, which tends at all times to move the shaft, 19, to the left, Fig. 1, as is easily understood by reference to the drawings, and thereby makes an airtight joint between the shaft, 19, and the body, 1.

Instead of having the conical shoulder, 26, bear against the body, 1, I may insert a

sleeve for it to find a seat on as shown in Fig. 1.

In order to facilitate manufacture, I insert in the body, 1, a member, 6, which forms a bearing for the spindle, 9, throughout its longitudinal axis, a valve seat, 30, at its upper end for the head, 10, and an abutment for the spring, 13, at its lower end. This member is held in place by the cap, 2 as shown. One or more openings, 31, in the member, 6, permit the flow of air through the valve.

In practice, it is often necessary to have a valve such as described, adapted to be operated manually to permit the air to pass therethrough in one direction, coupled with means to permit the air to pass through in the opposite direction automatically as a pressure relief feature. The valve shown in the present application is well suited for use in such a case. It is obvious that if the pressure of air in the connection, 28, is sufficient to raise either the valve 10, or the valve, 8, off its seat, then air will flow automatically from the connection 28 to the connection 2, and my device then acts virtually as a check valve.

The body, 1, at one side near the top, and above the member, 6, is provided with an outlet connection, 28, provided with a flange, 29, or other suitable means of making pipe connections thereto.

The normal positions of the parts of the valve are shown in the two figures. When it is desired to open the valve so as to permit air or liquid to flow from the inlet cap to the outlet, 28, the crank, 20, is moved clockwise, Fig. 2, thereby causing the cam, 18, to bear upwardly against the shoe, 15, carrying with it the sleeve, 5, which exerts pressure against the spring, 14, and at the same time opens the small valve head, 8, permitting a certain portion of the media under pressure from the inlet to pass through the ducts 11, into the outlet, and thereby overcome to a degree the pressure acting upon the large valve head, 10. The center portion, 30, of the sleeve, 5, after it has moved upwardly a short distance, bears against the bottom of the cup, 12, and causes the same to be moved upwardly by direct pressure from the cam, 18, thereby putting the spring, 13, under pressure, and carrying with it the valve, 9, integrally attached to the head, 10. In this way, communication is set up between the inlet and the outlet of the valve. The cam, 18, and the other parts are so arranged that when the hand is removed from the crank, 20, the parts assume their initial position, thereby closing the valve, so that no media can pass.

Having described my invention so any one skilled in the art to which it pertains, can make and use the same, what I claim, as

my invention, and wish to secure by Letters Patent is:

I claim:

In a device of the character described, the combination of a substantially cylindrical casing, a main valve therein, a relief valve for said main valve, a sleeve within said casing having a cam follower pivotally connected thereto, said sleeve being operatively related to said main valve and said relief valve and a cam engaging said follower whereby said sleeve is actuated to open said relief valve and said main valve in succession.

In testimony whereof, I affix my signature.

WILLIAM B. SMITH WHALEY.
